M. NODA

CLINICAL THERMOMETER TUBING

Filed March 16, 1921.

INVENTOR
Matsueaburo Noda
BY HIS ATTORNEYS
Darby, Darby

UNITED STATES PATENT OFFICE.

MATSUSABURO NODA, OF NEW YORK, N. Y.

CLINICAL-THERMOMETER TUBING.

Application filed March 16, 1921. Serial No. 452,670.

To all whom it may concern:

Be it known that I, MATSUSABURO NODA, a subject of the Emperor of Japan, and residing at New York, in the county and State 5 of New York, have made a certain new and useful Invention in Clinical-Thermometer Tubing, of which the following is a specification.

This invention relates to a new construction of prismatical clinical thermometer tubing.

The object of the invention is to provide a prismatical, clinical thermometer tubing, in which the mercury controlled by the temperature can be seen very easily, thereby greatly facilitating the readings taken from the thermometer.

A further object of the invention is to provide in a thermometer of the character set forth, means whereby the reflection of mercury may be utilized to effect facility in reading.

Further objects of the invention will appear more fully hereinafter.

The invention consists substantially in the construction, combination, location and relative arrangement of parts, all as will be more fully hereinafter set forth, as shown by the accompanying drawing, and finally pointed out in the appended claims.

Referring to the drawings,—

Fig. 1 is a view in elevation of a fragment of the thermometer embodying my invention;

Fig. 2 is a sectional view of the same taken on the line 2—2 of Fig. 1, and looking in the direction of the arrows.

The same part is designated by the same reference character wherever it occurs throughout the two views.

In accordance with my invention, I provide a tubing preferably of glass, and preferably substantially triangular in cross section, in which A is the apex of the substantially triangular structure, the other corners of which are designated B and C, whereby it will be apparent that the sides A, B, A, C, are formed thereby with base portion B, C. While I do not desire to be limited or restricted to the specific details of construction, I prefer to make the sides

A, B, and A, C, substantially flat, whereas 55 the shape of the base B, C, is immaterial, and may be flat, as in the case of the sides A, C, and A, B, or may be slightly curved as shown. At the center of the triangular glass tube structure is located the capillary tube D, behind which, as a reflector, therefor, is a member G, preferably made milky white in color, and may be formed of glass or any other suitable material as desired. The purpose of the member G is to reflect the 65 mercury K contained in the capillary tube D, by means of the projecting lights which come through the sides A, B, and A, C, in accordance with the prismatic reflecting light, so as to give an intensely magnified 70 mercury column reading at E, F, thereby enabling a speedy reading of the temperature which the mercury registers at E and F. If desired, as shown at H—H, on opposite sides of the prismatic structure, suitable 75 color lines, for example, red, may be inserted to more clearly define and assist in the locating and reading of the mercury column.

It will be seen from the foregoing that I 80 have provided an exceedingly simple thermometer structure wherein the reading of the mercury is greatly facilitated on account of the reflection of the mercury itself, and the location of which is greatly facilitated 85 by the lines of definition, for example, the red lines H—H. By means of these colored parallel lines at the reflecting surface of the mercury column, an effective target is obtained.

Many modifications and changes in details will readily occur to those skilled in the art without departing from the spirit and scope of my invention. Therefore, what I claim as new and useful and of my own invention 95 and desire to secure by Letters Patent is:

1. A prismatical thermometer comprising a substantially triangular transparent body, a mercury tube positioned in said body at the approximate center thereof, means forming a reflecting surface positioned behind said tube and extending substantially the length of the base of the triangular body, guide lines in said body on opposite sides of the mercury tube parallel therewith for

guiding the eye and index marks located near the apex of said triangular body for reading the position of the mercury column.

2. A clinical thermometer comprising a prismatical body having one face slightly curved, a mercury tube in said body, means forming a reflecting surface located within the prism near said curved face, colored

guide lines in said body opposite said reflecting means whereby said mercury reading is magnified and shown between said guide lines for easy reading. ¹⁰

In testimony whereof I have hereunto set my hand on this 14 day of March A. D., 1921.

MATSUSABURO NODA.
